UNITED STATES PATENT OFFICE.

WILLIAM J. DAVIS, JR., AND ALBERT P. NIRDLINGER, OF CHICAGO, ILLINOIS.

ADJUSTABLE FLOOD AND SPOT LIGHT.

1,140,880.

Specification of Letters Patent. Patented May 25, 1915.

Application filed November 2, 1914. Serial No. 869,901.

REISSUED

To all whom it may concern:

Be it known that we, WILLIAM J. DAVIS, Jr., and ALBERT P. NIRDLINGER, citizens of the United States, and residents of Chicago, Illinois, have invented a new and useful Improvement in Adjustable Flood and Spot Lights, of which the following is a specification, the objects of our invention being to dispose a lighting apparatus, which in the present instance consists, preferably, of a hydrogen incandescent lamp, in the path of a relatively adjustable reflector, so as to secure a comparatively efficient degree of concentration and projection of the rays; to 10 ventilate the apparatus so employed, and to provide means for modifying the light so reflected by the interposition of various colored screens or transparencies in the path of the rays and means for revolving and 15 tilting the apparatus to the desired focus. We accomplish such objects by means of the mechanism illustrated in the accompanying drawing, in which—

Figure 1 is a side elevation of the lantern, 25 resting on a focusing pedestal. Fig. 2 is a front elevation. Fig. 3 is a rear elevation. Fig. 4 is a section on line 4—4 of Fig. 2. Fig. 5 is a section on line 5—5 of Fig. 2. Fig. 6 is a cross section on line 6—6 of Fig. 30 1. Fig. 7 is an enlarged plan of detail of chimney showing long slides. Fig. 8 is a section on line 8—8 of Fig. 7. Fig. 9 is an enlarged detail of lamp bracket on line 9—9 of Fig. 10. Fig. 10 is a section on line 35 10—10 of Fig. 9. Fig. 11 is an enlarged section of adjustment of reflector on line 11—11 of Fig. 1. Fig. 12 is an enlarged elevation of chimney adjustment. Fig. 13 is an enlarged section on line 13—13 of 40 Fig. 12.

Like numbers refer to similar parts throughout the several views.

In detail, the focal lantern shell 1 of the mechanism we preferably make of metal 45 suitably finished to stand the comparatively great heat engendered in the use of the lamp. The shell 1 is provided with a projecting sleeve 2 and telescoping into the sleeve 2 is the movable sleeve 3 which is 50 provided with the hood 4 and which members 2, 3 and 4 form the chimney 5 which is adapted to ventilate the apparatus as shown by the course of the arrows under said hood. The ordinary contact socket 6 is adjustably 55 connected to the sleeve 3 by means of the brackets 7, 7, which are rigidly fixed to the

socket 6 and are operatively connected with the sleeve 3 by means of the screws 8, 8 which register with the threaded apertures 9, 9 provided in the brackets and operatively 60 reciprocate in the meshed slots 10, 10 provided in the sleeve 3 so as to permit the centering adjustment of the directions of the socket 6. The series of meshes forming the upper line of the slots 10 are adapted to permit the raising of the brackets 7 by loosening the screws 8 at whatever point in the slots 10 the brackets should require to be secured. The wires 11 pass from the contact in the socket 6 through the roof of the 70 hood 4. The lamp 12 screws in the ordinary way to the contact in the socket 6. A mica washer 13 is interposed above the film 12^a which forms the crater of the lamp to protect in a measure the upper members of 75 the lamp and the contact, from the heat of the lamp. The sleeve 2 is provided with 80 threaded lugs 14, which project outwardly through the tangent slots 15 provided in the sleeve 3 and secured by the thumbscrew 14^a 85 by which slots and lugs the manipulation of the sleeve by the grasp of the operator on the hood 4 imparts a combined rotary and longitudinal movement to the sleeve 3 so bearing the socket 6 and the lamp 12 attached as above described. The chimney 5 is 90 movably connected with the shell 1 by means of the screws and lugs 16 and a number of operatively overlapping plates 16^a and 16^b which are operatively connected by 95 means of the lugs 17 reciprocating in the slots 18 and are manipulated by means of the wheel 19 which is rigidly fixed to the threaded rod 20; the threads of the rod 20 register with threads provided in the aperture of the lug 21 which is rigidly fixed to the shell 1 and which rod is provided with 100 a collar 22 which is operatively connected with the socket 23 forming a groove and pin joint and rigidly fixed to the plate 16^c so that the turning of the rod 20 imparts a longitudinal movement to the chimney 5 and the lamp 12 thereto attached as above described, so that in operation the lamp 12 by means of the adjustment of the bracket 105 7 at the point of the screws 8 operating in the racks 10 with the relative combined rotating and longitudinal movement of the sleeve 3 as indicated by the tangent slots 15 and the longitudinal movement of the chimney by means of the wheel 19, the lamp 12 110 may be suitably adjusted in position before

the reflector 24. The periphery 25 of the reflector 24 snugly fills the barrel of the shell 1. On the back of the reflector is provided a socket 26 which is adapted to receive the ball 27 forming the end of the threaded rod 28, which passes through the threaded aperture 29 provided in the closure 30 of the shell 1 and which rod is provided with the wheel 31 suitable to the hand of the operator and by turning of which rod 28 the reflector may be moved longitudinally in the barrel of the shell, to the limit of the slots 32 which are provided in the shell 1 and which are adapted to receive the lugs 33.

15 The lugs 33 are rigidly fixed to the periphery 25 of the reflector 24 bearing the screws 33^a. Behind the reflector 24 the closure 34 of the shell 1 is provided with a gallery of perforations 35 and with the vent 35^a 20 for ventilating the shell. Further ventilation is provided by the ventilators 36 which are attached longitudinally along the shell 1 by means of the fastenings 37, the ventilation occurring as indicated by the course and direction of the arrows. A series of metallic guides 38 is attached to the muzzle of the shell 1 by means of the fastenings 39 and which guides are adapted to receive various screens 40 which are raised and lowered at will in the path of the rays by means of the lines 41 pulleys 42 and buttons 42^a and which are raised by the pull of the operator and lowered by gravity. The apparatus as a whole is mounted upon the pedestal 43 which is 25 provided with a socket 44 which is adapted to receive the horizontally revolving plug 45. The upper stock 46 of the plug is expanded and is provided with an aperture 47 which is adapted to receive the goose neck 48 which is rigidly fixed to the shell by means of the fastenings 49 and which is adapted to rotate in a vertical plane in said aperture 47 and is regulated and secured at the will of the operator by means of the 30 thumbscrew 50.

In order that the reflector 24 may be adjusted to the desired radial focus or posture any one or more of the series of screws 33^a 50 may be tightened or loosened to advance or retard the movement of the corresponding segment of the reflector when the same shall be moved by means of the threaded rod by the turning of the handle 31.

The adjustment of the brackets 7 in the 55 meshed slots 10 is intended primarily for roughly centering the fixture 6 and lamp 12 so that the crater 12^a of the lamp initially will be as near as may be in the path of the focal center of the reflector when the lamp 60 is first suspended in said chimney. After the crater shall be lighted and the focal aperture directed by means of the gooseneck and swivel, to the desired object, the operator, to obtain a more exact adjustment of the 65 lighted crater to the focal center of the re-

flector seizes the rim of the hood 4 and the wheel 31 and reciprocally manipulates the same in manner and for the purposes described.

We claim:

1. In lanterns, the combination with a ventilated focal apertured shell which is provided with a closure, of an adjustable ventilated chimney which is operatively secured to said shell and adapted to project and adjust a lamp in said shell, a reflector interposed between said lamp and said closure and opposing said focal aperture and adapted to reflect the rays from the crater of said lamp and project the same through the focal aperture of said shell, means for centering and adjusting said lamp, and means for operating said chimney substantially as described. 75

2. The combination with a focal apertured lantern shell, of a hooded chimney which is formed of a number of operatively telescoping sleeves adapted for expanding and contracting the height of said chimney and which is movably attached to said shell by means of a number of operatively overlapping shuffling leaves engagingly interposed to connect said chimney and said shell and adapted to shufflingly reciprocate upon one another for moving said chimney longitudinally along said shell, a reflector in said shell and opposing said focal aperture, a lamp suspended from the hood of said chimney and adapted to interpose the crater of said lamp between said reflector and said focal aperture, and means for centering and adjusting the crater of said lamp to the radial focus of said reflector, substantially as described. 90

3. In adjustable flood and spot light chimneys the combination with a lantern shell which is provided with a suitable aperture, of a chimney leading from said aperture and formed of a sleeve which is provided with a tangent slot and a telescoping sleeve which is provided with a lug which projects through said slot and which lug is provided with a thumbscrew and is adapted to reciprocate in said slot to provide a combined rotating and longitudinal motion to said sleeve, a hood which is fixed to said sleeve and provides a ventilating aperture between the under surface of said hood and the adjacent periphery of said sleeve, a plate secured to the lower periphery of said telescoping sleeve, and is provided with a lug, an overlapping plate which is secured to said shell and is provided with a slot and is adapted to register with said lug and permit a reciprocating movement of said lug and means for sliding said chimney longitudinally across said chimney aperture in said shell substantially as described. 105

4. In flood and spot lights the combination with a lantern shell which is provided 110

115

120

125

with a focal aperture, a closure opposed to said focal aperture, a series of slots near said closure, a chimney disposed between said focal aperture and said closure and a lamp 5 disposed under said chimney, of an adjustable reflector within said shell and backed against said closure and opposingly facing said lamp and focal aperture, a series of lugs fixed to the periphery of said reflector and 10 extending movably through said slots and provided with thumbscrews, a socket fixed to the center of the rear surface of said reflector and adapted to receive the ball-like end of a threaded rod, said threaded rod

passing through a correspondingly threaded 15 aperture provided in said closure and provided with a wheel-like handle which is adapted to revolve said threaded rod for moving said rod longitudinally and adjusting said reflector in said shell, substantially 20 as described.
